UNITED STATES PATENT OFFICE.

JOSEPH DELASSUE, OF PARIS, FRANCE.

DEVICE FOR AUTOMATICALLY REGULATING THE SUPPLY OF STEAM TO GAS-PRODUCERS.

No. 829,060.

Specification of Letters Patent.

Patented Aug. 21, 1906.

Application filed December 22, 1903. Serial No. 186,236.

To all whom it may concern:

Be it known that I, JOSEPH DELASSUE, a citizen of the French Republic, residing at 7 Rue Chorol, Paris, France, have invented 5 certain new and useful improvements in a device for automatically regulating the supply of steam to a gas-producer operating in conjunction with an internal-combustion engine, of which the following is a specification. 10 This invention has reference to a device for regulating the supply of steam to gas-producers operating in conjunction with gas-engines.

Gas-producers subject to the direct suction 15 of the gas-engine piston are becoming more and more recognized as the most desirable solution of the problem of obtaining motive power on account of the absence of danger and their great economy, which is such that 20 no other practicable source of energy can compete against them. There are, however, still certain inconveniences to be overcome, among which may be mentioned the imperfect automatic regulation of the steam-supply 25 to the producer and the fact that the apparatus for washing and purifying the gas has to be very bulky if it is to be effective. Moreover, the wear and tear on the opening or twyer for the entry of air and steam at the 30 bottom of the producer rapidly sets up disturbances in the regular action of the producer by reason of the increase in diameter of this opening. Now these disadvantages are obviated by the device shown in the annexed drawings, in which—

Figure 1 represents the general construction of the improved producer and purifier in vertical section on the line 1 1 of Fig. 2. Fig. 2 represents a horizontal section on the line 40 3 3. Figs. 3 and 4 show, respectively, in transverse section and in plan a special hollow ring-piece or twyer through which the steam and air are admitted.

For the purpose of illustration the regulating device is shown set up in connection with a gas-producer A and a purifier S, serving both as a condenser or cooler and also for washing or scrubbing the gas.

The producer comprises a cast-iron body 50 A, provided internally with a fire-brick lining B, which contains the charge of fuel C, the latter resting on a hollow sole or bottom D, and this latter forms the evaporator for generating the steam to supply the producer.

Between the body A and the sole D is arranged the cast-iron ring-piece E, wherein is

the twyer-opening E', Figs. 3 and 4, through which the air and steam are drawn into the body A of the producer. The opening E' is to be kept at such a temperature that the 60 metal is not liable to be attacked by the steam, and to this end the ring-piece E is made hollow, as shown, and has a downward projection or offset, so that it will be in contact with the evaporator D at the points e e' 65 and will be thereby kept cool. It is furthermore cooled by the passage through or round its interior of the steam which it serves to deliver to the gas-producer.

The steam produced in the evaporator D 70 flows by the passage F to the regulating-valve G and from there returns by the passage F' into the ring-piece E, whence it passes out by the small holes H, so as to be drawn through the opening E' after being mixed with the 75 air.

The evaporator D has an upward projection on its right corresponding to the downward projection on the ring E. Hence the superposition of the latter on the evaporator 80 forms between the projections a passage I of rectangular section, open at each extremity. It is by the open ends of this passage I that the air enters the producer and that the bottom of the furnace is cleaned out. 85

In order that in a producer where the gas is aspirated directly by the piston of the engine the action of the latter may always be regular, it is necessary when the engine is working with a full charge that the admission 90 of steam should be at the maximum. When the engine is working with a variable charge, the proportion of steam passing into the producer should be diminished accordingly and in proportion to the smaller demand of 95 work of the engine until finally the introduction of steam shall be completely stopped, when the engine runs light without taking in its charge. This adjustment is necessary if it be desired to avoid too great a drop in the 100 temperature of the producer-furnace, due to a mixture (of air and steam) excessively rich in steam, such as results when the suction is diminished—that is to say, when the regulator checks the suction of the gas. 105

Now according to the present invention the result stated above is obtained by causing the steam issuing from the evaporator D (for delivery into the bottom of the producer) to pass through the regulating-valve G, which 110 is so set that when the motor is running light it occupies the position indicated in Fig. 1 of

the drawings. In this position all the steam escapes by the orifice *g* and never enters the furnace. In proportion, however, to a greater demand of work upon the motor the valve turns, and so brings the two steam-passages *F* and *F'* into communication. At this moment more and more of the steam is sent into the producer and less and less escapes by the orifice *g*. When the two passages *F* and *F'* are in full communication, the orifice *g* is closed and all the vapor is sent to the producer.

The following is an explanation of the regulating mechanism by which the different positions of the valve *G* are obtained according to the quantity of gas drawn in by the motor. On the suction-valve of the gas-engine or on one of the parts which operate this valve there is arranged a suitable device—say, for instance, a stud or projection—which imparts a to-and-fro movement to a system of rods and levers analogous to a bell-crank arrangement of which the last rod is shown at *J*. Between this rod *J* and the rod *n*, which operates the valve *G*, is arranged the regulating mechanism.

In a suitable frame or support *K*, secured to the body of the producer, are arranged two shafts *M* and *N*, connected together by means of gear-wheels *m n*. On the shaft *N* is wound a helical spring *O*, the ends of which are held in such manner to cause the gear-wheels *m n* to rotate.

On the shaft *M* is keyed a double ratchet-wheel *P P'*, of which the one *P'* has a continuous row of teeth, the teeth of the other, *P*, being interrupted from place to place for the reasons hereinafter explained. In order to facilitate the construction of this double ratchet-wheel and to allow the cutting off of a number of teeth from the wheel *P* without injury for the teeth of the adjacent wheel *P'*, a groove *p* is left between the said wheels.

On the wheel *P* rests a driving-pawl *1*, pivoted on a lever *2*, loose on the shaft *M*, said lever being connected with the rod *J*. A suitable spring *3* always presses the driving-pawl *1* on the wheel *P*. On the wheel *P'* acts a check-pawl *4*, pivoted on an axis *5*, secured to the frame *K*, and this check-pawl is pressed on the wheel *P'* by a spring *6*. Finally a crank-disk *7*, keyed on the end of the shaft *M* opposite the wheel *m*, is connected with the rod *n*, which operates the valve *G*. This mechanism works as follows:

Each time that the suction-valve of the gas-engine is moved in a known manner to open said valve the rod *J* is pressed down and the driving-pawl *1* drives the wheel *P*, thus closing the valve *G* by means of the shaft *M*, the crank-disk *7*, and the rod *n*. The check-pawl *4* prevents the back movement of the wheel *P P'* until the pawl *1* has come back, at which time its axis *5* presses on the tail end *9*

of the check-pawl *4*, which thereby becomes disengaged from the wheel *P'*. In the same time the tail end *10* of the pawl *1* strikes against a stop *11* on the frame *K* and becomes disengaged from the wheel *P*. The double ratchet-wheel *P P'*, therefore, is set free and is allowed to rotate under the action of the spring *O*, which action is transmitted to the shaft *M* by means of the gear-wheels *m n*. The speed of this return movement is such that between two consecutive suction-strokes of the engine the wheel returns by more than half—say, for instance, two-thirds—of the forward path that has been previously imparted to it by the driving-pawl *1*. This speed, moreover, can be regulated by means of an adjustable brake *12*, working on the crank-disk *7*. The brake-shoe *12* is pressed against the crank-disk by means of a spring *13* and a screw *14*. When the teeth of a part of the ratchet-wheel *P* are worn out, this wheel is turned on its axis the required distance, so that fresh teeth are brought into engagement with the pawls.

To make the matter more clear, suppose that the pawl *1* at each suction-stroke of the engine turns the wheel *P* through three teeth. The return movement imparted to the said wheel by the spring *O* will be two teeth. Then if the engine is developing its maximum power and if the suctions of gas by the motor are proceeding without interruption the wheel *P* will be advanced actually by one tooth only for each suction-stroke, and so on until the valve *G* brings the passages *F* and *F'* into full communication at the point where the teeth of the wheel *P* end, whereupon the parts become practically stationary, and the admission of steam to the producer is at a maximum. If there should be a less demand on the power of the engine, and consequently a diminution in the suction of the gas, the wheel *P* turns back through four teeth, because it returns by two teeth between each two suctions, (one of which is of course supposed now to be missed;) but as at the following suction it will be advanced by three teeth the sum of the actions is that it returns by one tooth only, and hence the valve *G* will be closed by a corresponding amount. Should there be two consecutive omissions of the suction, the wheel *P* will return by six teeth and only advance by a space of three teeth. At the following suction the valve *G* will therefore close a little farther still, and this will go on until the engine runs light, the omissions or misses being then, say, from three to four for one admission or suction. At that time the wheel *P* will have returned to its point of starting, the communication between the passages *F* and *F'* will be interrupted, and no steam will be admitted to the producer, because the first movement produced by a single suction serves only to uncover the solid

part or wall separating the orifice F from the orifice F'. Hence by this means when the motor is in full work the admission of steam to the gas-producer is at a maximum. It diminishes gradually in proportion as the charge drawn in diminishes. The suction also diminish and at length ceasing to the extent explained when the motor is running light.

10 The fuel or coal is introduced during working into the gas-producer by an apparatus or air-lock Q, having a double closing arrangement, and the gas passes from the producer by the passage R, whereby it is led into the

15 washer or scrubber S. This latter is composed of a mass or column of coke, separated into two parts by the walls or webs s s', which have left between them a space α^2 for the passage of the gas coming from the producer.

20 These walls, kept cool by the washing-water which is sprayed on the column of coke, serve to cool the gas, and the products of condensation fall into the waste-pan T along with any powder carried away by the wash-water.

25 The gas issuing from the lower part of the condenser-space s^2 ascends and traverses the column or pile of coke and finally flows out by the openings U on its way to engine.

The condenser and the washer or scrubber 30 have been thus combined in one apparatus in order to diminish the cost and the space required.

35 The apparatus shown may be modified when desirable in carrying the invention into practice without altering the general principle.

I claim—

1. In a gas-producer operating by the direct suction of the engine-piston, the combination of means for regulating the mixture of air and steam aspirated, a mechanism for coupling the said means with the suction-valve of the gas-engine.

2. A device for automatically regulating 45 the supply of steam to a gas-producer operating in conjunction with an internal-combustion engine embodying an adjustable valve for opening and closing a steam-passage communicating with the producer, and means 50 operated by the suction-valve mechanism of the engine for controlling the movement of said valve.

3. A device for regulating the supply of steam to a gas-producer operating in conjunction with an internal-combustion engine embodying an automatically-adjustable valve for opening and closing a steam-passage communicating with the producer, and means 55 operated on the suction-stroke of the engine for controlling the movement of said valve.

4. A device for regulating the supply of steam to a gas-producer operating in conjunction with an internal-combustion engine embodying an automatically-adjustable

valve for opening and closing a steam-passage communicating with the producer, and means operated by the suction-valve mechanism of the engine for controlling the movement of said valve.

5. A device for automatically regulating the supply of steam to a gas-producer operating in conjunction with an internal-combustion engine embodying an automatically-adjustable means for opening and closing a 75 steam-passage communicating with the producer, and mechanism operated on the suction-stroke of the engine for controlling the said means.

6. A device for positively and automatically regulating the supply of steam to a gas-producer operating in conjunction with an internal-combustion engine, a double ratchet-wheel, a valve connected therewith, operated thereby and adapted to open and 85 close a steam-passage communicating with the producer, and means for automatically operating said wheel on the suction-stroke of the engine.

7. A device for automatically regulating 90 the supply of steam to a gas-producer operating in conjunction with an internal-combustion engine, comprising a double ratchet-wheel, a driving-pawl therefor, a valve connected with said wheel, operated thereby and 95 adapted to open and close a steam-passage communicating with the producer, thereby regulating the supply of steam to the producer, a pawl adapted to engage said wheel to prevent back rotation, means for automatically operating said driving-pawl on the suction-stroke of the engine, said driving-pawl moving said wheel in one direction, means for automatically moving said wheel in a counter direction, and means for disengaging said pawls to enable the movement of 105 said wheel in the counter direction.

8. A device for automatically regulating 110 the supply of steam to a gas-producer operating in conjunction with an internal-combustion engine, comprising a valve for opening and closing a steam-passage communicating with the producer, thereby regulating the supply of steam thereto, means for controlling the movement of said valve, and means 115 for automatically and intermittently operating said controlling means in alternate directions, the movement in one direction being greater than the other.

9. A device for positively regulating the 120 supply of steam to a gas-producer operating in conjunction with an internal-combustion engine, comprising a continuous and a mutilated ratchet rotating in unison, a driving-pawl engaging said mutilated ratchet for imparting movement to said ratchets in unison, a steam-valve connected with said ratchets, operated thereby and adapted to open and close a steam-passage communicating with the producer, thereby regulating the supply 125 130

- of steam thereto, a pawl adapted to engage said continuous ratchet to prevent back rotation of the said ratchets, means for automatically moving said ratchets in unison in a counter direction, and means for disengaging the said pawls to enable the movement of the said ratchets in the counter direction.
10. A device for automatically regulating the supply of steam to a gas-producer operating in conjunction with an internal-combustion engine, comprising an automatically-operable valve adapted to open and close a steam-passage communicating with the producer, a rotatable element connected with said valve and adapted to operate it, and a driving element operated by the suction-stroke of the engine and adapted when operated to impart movement to said rotatable element.
15. 11. A device for automatically regulating the supply of steam to a gas-producer operating in conjunction with an internal-combustion engine, comprising an automatically-operable valve adapted to open and close a steam-passage communicating with the producer, a rotatable element connected with said valve and adapted to operate it, a driv-
- ing element operated by the suction-stroke of the engine and adapted when operated to impart movement to said rotatable element, 30 means for automatically moving said rotatable element in a direction opposite to that imparted by the driving element, and means for disengaging said driving element from said rotatable element to permit of the 35 movement of the rotatable element in the direction opposite to that imparted thereto by the driving element.
12. The combination with a gas-producer working by the suction action of an internal-combustion engine, of means for automatically regulating the supply of steam to said producer, said means involving a valve adapted to open and close a steam-supply passage communicating with the producer, and means 40 operated by the suction-stroke of the engine for controlling the movement of said valve.
- In testimony whereof I have hereunto set my hand in presence of two subscribing witnesses.
